**NURSING BOTTLE NIPPLE WITH
CONTROL VALVE**

Henry W. Witz, Barrington, Ill., assignor to Nursmatic Corporation, Chicago, Ill., a corporation of Delaware

Application October 30, 1957, Serial No. 693,280

5 Claims. (Cl. 128—252)

This invention relates to improvements in a valved nipple for a baby's nursing bottle and refers particularly to a valved nipple which facilitates extraction of the milk or other liquid baby food from a nursing bottle by the infant.

Conventional nipples for baby bottles have a relatively small hole or holes at their tip and the hollow portion of the nipple communicates with the interior of the bottle through a relatively large opening substantially the size of the mouth of the bottle. Hence, when the baby feeds, exerting a biting or "gumming" action upon the nipple, the liquid in the nipple is more readily forced back into the bottle than through the small hole or holes in the tip. In order to receive the liquid, the baby must exert a sucking action which results in the baby swallowing excessive amounts of air. Excessive air swallowing frequently causes aerophagia, the basic cause of so-called colic.

Valves have heretofore been proposed for nipples to control the back flow of liquid, hereinbefore described, but valves heretofore proposed have been complicated, expensive, difficult to clean in many instances, unreliable in operation.

The present invention contemplates a nipple valve for preventing and controlling the back flow of liquid, hereinbefore described, the valve being simple in construction and operation, removable and easy to clean and extremely reliable.

Other features and advantages of the invention will be apparent from the accompanying drawing and following detailed description.

In the drawing,

Fig. 1 is a fragmentary sectional view of a conventional nursing bottle having a valved nipple embodying the features of the present invention.

Fig. 2 is a view similar to Fig. 1 showing the nipple compressed and the valve seated.

Fig. 3 is an enlarged perspective view of the valve member employed.

Fig. 4 is a plan view of the valve member shown in Fig. 3 illustrating particularly the spacer flange carried by said member.

Referring in detail to the drawing, 1 indicates a conventional baby's nursing bottle, having a mouth 2, the external portion of which carries threads 3 formed integral with the glass bottle. A nipple 4 is removably carried at the mouth of the bottle and may be constructed of conventional elastic, resilient material, such as, rubber, silicon rubber or the like. The base of the nipple carries a radial flange 5 which defines a relatively large opening 6 which affords communication between the interior 7 of the nipple and the interior of the bottle 1. The flange 5 is adapted to seat on the mouth 2 of the bottle and an internally threaded screw cap 8 of hard rubber, plastic or the like, functions to clamp the flange in liquid-tight position upon the bottle mouth.

The nipple 4 has a conventional bulbous tip 9 which is provided with one or more relatively small holes 10

2

through which the liquid within the nipple may be extracted by the infant. Adjacent the mouth 6, an inwardly extending annular flange 11 is carried and above said flange a relatively enlarged compartment 12 is provided in the nipple. As will be hereinafter more fully described, a valve 13 engages with flange 11 and a portion of the valve is carried in the compartment 12.

The compartment 12 is defined by the nipple flange 11, side wall 14 of an enlarged portion of the nipple and an annular shoulder 15 formed in the interior of the nipple, said shoulder terminating in an inwardly extending tubular flange 16. The compartment 12 is in communication with the interior 7 of the bulbous portion 9 of the nipple. As will be hereinafter more fully described the tubular flange 16 functions as a stop to restrict inward movement of the valve 13.

The valve 13 may be constructed of a lightweight material such as aluminum, plastic or other light-weight material which can readily withstand sterilizing temperatures. The valve comprises a cylindrical portion 17 which is of a diameter less than the inner diameter of nipple flange 11, the difference in diameters being such that the valve cylindrical portion 17 may move freely in the space defined by the nipple flange and liquid 18, carried in the bottle 1, may flow through the clearance space between the nipple flange and said cylindrical portion of the valve.

The cylindrical portion 17 of the valve terminates at one end in a radial flange 19 which is joined to the cylinder by a large angle conical surface 20. The opposite side of the flange is substantially flat except that a substantially arcuate rib 21 projects from said flat side, the rib, as will be hereinafter more fully described, functioning as a spacer flange in limiting the movement of the valve in the nipple.

When the valve 13 is disposed in operative position in the nipple, the flanged portion of the valve is disposed in the enlarged compartment 12. The valve flange 19 can, during assembly, very readily be urged through the opening defined by the nipple flange 11 due to the resiliency and elasticity of the nipple flange since said nipple flange may very readily be temporarily deformed to permit insertion of the flanged portion of the valve into the compartment 12. To facilitate the insertion or removal of the valve in and from the nipple a handle or knob 22 is formed upon the bottle-end of the valve.

When the valve 13 is positioned in the compartment 12 and the nipple is undistorted, as shown in Fig. 1, the valve flange 19 is spaced from the nipple flange 11 when the spacer flange or rib 21 is in contact with the tubular flange 16, or vice versa, when the valve flange 19 is in contact with the nipple flange 11, the spacer flange or rib 21 is spaced from the tubular flange 16. When flanges 19 and 11 are spaced, liquid 18 can flow past the cylindrical portion 17 of the valve, and around nipple flange 11 and valve flange 19 into the compartment 12 and space 7. Thus, when the bottle 1 is inverted, the pressure of the liquid 18 in the bottle and gravity tend to unseat the valve flange 19 and permit the filling of the nipple. The unseating of the valve flange is relatively slight, being controlled by spacer rib 21 making contact with the tubular flange 16.

The position of the bottle and valve in Fig. 1, hereinbefore described, is the normal feeding position of said parts. Hence, when the bottle is inverted or inclined, the interior of the nipple is initially filled with milk or liquid baby food from the bottle. The infant instinctively reacts to bite or "gum" the nipple thereby distorting it and subjecting the liquid therein to pressure. The initial establishment of this pressure causes the valve to seat, that is, flange 19 seats upon nipple flange 11 and further when the wall 14 of the nipple is distorted the

tubular flange 16 moves along the arcuate rib 21 and tends to force the valve downwardly to seat valve flange 19 more firmly into contact with the nipple flange 11. Thereafter, further pressure upon the nipple projects the liquid through the holes 10 to the infant's mouth. The biting or "gumming" of the nipple is an intermittent operation and each time the bite is released, the valve 13 opens and permits additional liquid to enter the nipple. During the feeding operation these actions are alternately repeated.

By virtue of the spacer flange or rib 21 and its proximity to the tubular flange 16, the movement of the valve is small and the valve responds very quickly to the change of pressure conditions in the nipple. Moreover, when the nipple returns from the distorted position of Fig. 2 to the normal position of Fig. 1, the volume of the nipple increases and establishes a reduced pressure in the nipple tending to hasten the flow of liquid from the bottle to the nipple.

In view of the fact that substantially no sucking action is required by the infant, excessive air swallowing is prevented. Further, since a positive liquid pressure is established in the nipple, clogging of the small holes 10 is prevented since the pressurized liquid forces through any particles that would normally clog the holes.

Another advantage of the present device resides in the fact that when the bottle is turned upright, the flange 19 seats very lightly on the flange 11, since it is now not subject to the internal biting pressure, and the residual liquid in the nipple flows back into the bottle or can be made to do so by a slight shaking of the bottle. This is of extreme importance since during the warming of the liquid, if liquid were confined in the nipple and such liquid were tested for warmth, it would normally be cooler than the liquid in the bottle, and based on the temperature of the confined nipple-liquid a false test would result which might lead to serious consequences when the liquid in the bottle, which may be considerably warmer than the test liquid, is fed to the baby.

Since the basic structure of the conventional nipple is not materially altered the nipple can be readily cleaned and in view of the simplified structure of the valve, it also can be readily cleaned. In addition, the nipple with the valve in place may be readily sterilized as a unit.

Modifications of the present invention which do not depart from the spirit of the invention may readily occur to those skilled in the art and, hence, it is not intended that the present invention be limited to the exact details shown and described except as necessitated by the appended claims.

I claim as my invention:

1. A valve controlled nursing bottle nipple comprising a flexible, resilient nipple having a relatively small feeding opening at one end and a relatively enlarged charging opening at the opposite end, said nipple being adapted to be carried on the mouth of a nursing bottle with its charging opening in communication with the interior of the bottle through said mouth, an annular flange carried by said nipple adjacent said charging opening and extending radially inwardly into said charging opening, an annular shoulder carried upon the interior wall of the nipple intermediate the feeding opening and the charging opening, a valve loosely positioned in the space defined by said nipple flange, a flange carried by said valve within said nipple and in overlapping relationship to said nipple flange, and a spacer rib carried by said valve extending transversely to said valve flange within said nipple which is disposed adjacent said shoulder and limits inward movement of said valve relative to said nipple by contacting said shoulder.

2. A valve controlled nursing bottle nipple comprising a flexible, resilient nipple having a relatively small feeding opening at one end and a relatively enlarged charging opening at the opposite end, said nipple being

adapted to be carried on the mouth of a nursing bottle with its charging opening in communication with the interior of the bottle through said mouth, an annular flange carried by said nipple adjacent said charging opening and extending radially inwardly into said charging opening, an annular shoulder carried upon the interior wall of the nipple intermediate the feeding opening and the charging opening, a valve loosely positioned in the space defined by said nipple flange, a flange carried by said valve within said nipple and in overlapping relationship to said nipple flange whereby said valve flange may seat upon said nipple flange, and a spacer rib carried by said valve extending transversely to said valve flange within said nipple which is disposed adjacent said shoulder and limits inward movement of said valve relative to said nipple by contacting said shoulder when the valve flange is unseated relative to the nipple flange.

3. A valve controlled nursing bottle nipple comprising a flexible, resilient nipple having a relatively small feeding opening at one end and a relatively enlarged charging opening at the opposite end, said nipple being adapted to be carried on the mouth of a nursing bottle with its charging opening in communication with the interior of the bottle through said mouth, an annular flange carried by said nipple adjacent said charging opening and extending radially inwardly into said charging opening, an annular shoulder having a tubular flange carried upon the interior wall of the nipple intermediate the feeding opening and the charging opening, a valve loosely positioned in the space defined by said nipple flange, a flange carried by said valve within said nipple and in overlapping relationship to said nipple flange, and an arcuate spacer rib carried by said valve extending transversely to said valve flange within said nipple which is disposed adjacent said tubular flange and limits inward movement of said valve relative to said nipple by contacting said tubular flange.

4. A valve controlled nursing bottle nipple comprising a flexible, resilient nipple having a relatively small feeding opening at one end and a relatively enlarged charging opening at the opposite end, said nipple being adapted to be carried on the mouth of a nursing bottle with its charging opening in communication with the interior of the bottle through said mouth, an annular flange carried by said nipple adjacent said charging opening and extending radially inwardly into said charging opening, an annular shoulder carried upon the interior wall of the nipple intermediate the feeding opening and the charging opening, a valve comprising a cylindrical portion loosely positioned in the space defined by said nipple flange, a flange carried by the cylindrical portion of said valve within said nipple and in overlapping relationship to said nipple flange whereby said valve flange may seat upon said nipple flange to interrupt communication through said charging opening, and a spacer rib carried by said valve extending transversely to said valve flange within said nipple which is disposed adjacent said shoulder and limits inward movement of said valve relative to said nipple by contacting said shoulder when the valve flange is unseated from said nipple flange.

5. A valve controlled nursing bottle nipple comprising a flexible, resilient nipple having a relatively small feeding opening at one end and a relatively enlarged charging opening at the opposite end, said nipple being adapted to be carried on the mouth of a nursing bottle with its charging opening in communication with the interior of the bottle through said mouth, an annular flange carried by said nipple adjacent said charging opening and extending radially inwardly into said charging opening, an annular shoulder carried upon the interior wall of the nipple intermediate the feeding opening and the charging opening, a valve loosely positioned in the space defined by said nipple flange, a flange carried by said valve within said nipple and in overlapping relationship to said nipple flange, and an arcuate spacer rib

carried by said valve extending transversely to said valve flange within said nipple toward said shoulder and which is disposed adjacent said shoulder, said shoulder when said nipple is distorted by an infant extracting liquid from the nipple moving toward said spacer rib to 5 urge said valve flange toward said nipple flange.
